G. M. DAVIS

FUSE BOX

Filed July 11, 1924

R. J. Thomas

George M. Davis INVENTOR
BY Victor J. Evans

WITNESS:

UNITED STATES PATENT OFFICE.

GEORGE M. DAVIS, OF ST. LOUIS, MISSOURI.

FUSE BOX.

Application filed July 11, 1924. Serial No. 725,477.

To all whom it may concern:

Be it known that I, GEORGE M. DAVIS, a citizen of the United States, residing at St. Louis, in the county of St. Louis City 5 and State of Missouri, have invented new and useful Improvements in Fuse Boxes, of which the following is a specification.

This invention relates to a fuse box, the general object of the invention being to provide means whereby a simple rotary movement of a member in the box will bring a new fuse into operative position when another fuse has been destroyed.

Another object of the invention is to provide means for rotating the member without opening the case.

This invention also consists in certain other features of construction and in the combination and arrangement of the several 20 parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a plan view of the device with 30 the cover removed.

Figure 2 is a section on line 2—2 of Figure 1.

Figure 3 is a section on line 3—3 of Figure 2.

Figure 4 is a section on line 4—4 of Figure 2.

Figure 5 is a view of one of the fuses.

Figure 6 is a view of the spring contact member for connecting the fuse carrier with 40 the supply conductor.

In these views, 1 indicates a case which is adapted to be closed by the cover 2. A partition 3 is supported by the bolts and sleeves 4 so that the case is divided into two 45 horizontal chambers. A shaft 5 is vertically arranged in the partition for rotary movement and the lower end of said shaft carries a gear 6 which is engaged by a worm 7 on a shaft 8 which is journaled in the lower 50 chamber and which has its cranked end 9 extending through the wall of the case 1. A disc 10, formed of insulating material, is suitably connected with the shaft 5 and is located in the upper chamber. This disc 55 carries a plurality of posts 11, each of which is provided with a vertically arranged socket

threaded to receive a screw 12 which is designed to clamp the fuse members 13 in the holes 14, made in the posts. These fuse members 13 are each formed with a tapered 60 head 15 which is provided with an elongated opening 16 for engaging a pin 17 carried by a post 18 supported by the partition 3 and to which one of the main conductors 19 is connected. The other conductor 20 is connected with a post 21 to which a spring member 22 is fastened, the notched inner end 23 of which engages a ring 24 of conducting material on the disc 10 which is connected by the conducting strips 25 with the posts 11 70 on said discs.

From the above it will be seen that when the disc is rotated by turning the shaft 8 through means of its crank handle 9, one of the fuse members 13 will be brought to a 75 position where the pin 17 will pass into the opening 16 and make electrical contact with the same. The current can then pass from conductor 20 through the spring strip 22 to ring 24 on the disc and from said ring 24 80 through strip 25 to posts 11, the fuse 13, pin 17 to conductor 19. When the fuse 13 is destroyed it is simply necessary to give the shaft 8 a partial rotation to move the disc 10 a sufficient distance to place the next fuse 85 13 in engagement with the pin 17. When all the fuses have been destroyed new ones can be easily and quickly put in place by loosening the clamping screws 12 and placing the stems of the new fuses in the holes 14 and 90 then tightening the screws 12 to hold the new fuses in place in the posts 11. With my invention it is not necessary to open the box to place a new fuse in position as all that is necessary is to give the shaft 8 a partial 95 movement through the crank 9 which is located outside the box.

It is thought from the foregoing description that the advantages and novel features of my invention will be readily apparent. 100

I desire it to be understood that I may make changes in the construction and in the combination and arrangement of the several parts, provided that such changes fall within the scope of the appended claims. 105

What I claim is:—

1. A device of the class described comprising a casing, a rotary member therein, means for rotating the member from outside the casing, a plurality of fuse carrying members 110 on the rotary member, a fuse carried by each member, a pair of terminal posts adapted to

be connected with the conductors leading to the box, a pin carried by one post and adapted to be engaged by a fuse and a brush connected with the other post and engaging a part on the rotary member which is electrically connected with the fuse carrying members.

2. A device of the class described comprising a casing, a pair of terminal posts therein adapted to be connected with a pair of conductors, a shaft journaled in the casing, a disc connected therewith, a crank shaft

geared to the shaft and having its cranked end extending through the casing, a plurality of posts carried by the discs, a fuse 15 detachably connected with each post, a pin on one of the terminal posts arranged to be engaged by a fuse, a ring on the disc electrically connected with the fuse carrying post and a brush engaging the ring and connected 20 with the second terminal post.

In testimony whereof I affix my signature.

GEORGE M. DAVIS.
